UNITED STATES PATENT OFFICE

ROBERT L. BROWN, OF MILWAUKEE, WISCONSIN, ASSIGNOR TO THE HARNISCHFEGER CORPORATION, OF MILWAUKEE, WISCONSIN

CONVEYER

Application filed December 29, 1926. Serial No. 157,646.

This invention relates in general to trenching machines and more particularly to an improved spoil conveyer for trenching machines.

Among the objects of the invention are to provide a spoil conveyer which may be readily, easily and quickly converted from a straight type or free hinge type to the so called cradle type; to provide a spoil conveyer of this character which may be quickly shifted laterally on one side of the machine or from one side of the machine to the other without involving laborious and time consuming bolting and unbolting or dismantling or drive changing operations and without subjecting the parts of the conveyer or the shifting means to heavy or sudden strains; to provide a conveyer of this character which has the advantages mentioned and which also has the capacity of elevating the spoils so as to load a truck or accomplish any other purpose involving the elevation of the spoil and this, even when the conveyer has been shifted in; to provide a spoil conveyer which may be readily, quickly and easily hoisted to any practical height at which it may be desirable to discharge the spoil or elevated to an upright position when the trenching machine is traveling from place to place; to provide a spoil conveyer having a single frame member made up of a plurality of sections connected together by releasably lockable hinges; to provide a novel chain shifting mechanism having yieldable connection with the frame of the spoil conveyer and serving to impart the proper shifting movement to the same in various angular adjustments on the sections thereof while permitting the spoil conveyer to be supported at two spaced points and compensating for the differential resulting from the conveyer frame breaking at a hinge center not concentric with the link pin of the shift chain; to provide a spoil conveyer which is held against upward or lateral displacement as well as properly supported; to provide a spoil conveyer in which the spilling of the spoil is minimized and in which any spoil spilled is deflected away from the operating parts of the conveyer; and in general to provide a spoil conveyer which is simple,

strong, durable and rigid in construction, which is easily and quickly controlled and adjusted, which is reliable and effective in operation, and which is easy and comparatively inexpensive to manufacture.

Other objects and advantages reside in certain novel features of the construction, arrangement and combination of parts, which will be hereinafter more fully described and particularly set out in the appended claims, reference being had to the accompanying drawing forming a part of this specification, and in which:

Figure 1 is a view in side elevation showing a trenching machine having a spoil conveyer embodying the present invention embodied therein.

Figure 2 is a view in a transverse vertical section taken on line 2—2 of Figure 1 and looking in the direction of the arrows.

Figure 3 is a fragmentary plan view of the spoil conveyer, parts being shown in sections.

Figure 4 is a fragmentary view of the conveyer and its mounting showing the same partly in elevation and partly in central vertical longitudinal section, and

Figure 5 is a view in section on line 5—5 of Figure 4.

Referring to the drawings, numeral 1 designates generally a trenching machine. This machine is well known in the art and the buckets 2 of its digging means discharges the spoil or dirt onto a spoil conveyer designated generally at 3 and which extends transversely of the trenching machine to deliver the spoil or dirt to the desired point laterally of the trenching machine.

The conveyer 3 comprises a single frame member designated generally at 4 and which extends longitudinally and centrally of the conveyer structure generally and is made up of a plurality of sections 5 of substantially inverted channel shape in cross section. Preferably four sections 5 are embodied in the embodiment of the invention illustrated. Hinges designated generally at 6 are provided for hingedly connecting the adjacent ends of adjacent sections, whereby the sec-

tions of the frame may be adjusted angularly relative to each other.

Each hinge 6 comprises a pair of hinge members designated at 7 and 8. The hinge member 7 has an attaching portion 9 which engages and is secured to its section of the frame member. Apertured hinge ears 10 are integrally formed with the attaching portion 9 of the member 7 and rearwardly of the hinge ears 10 apertured lock lugs 11 are provided, the lock lugs 11 being integral with the apertured hinge ears 10 and with the attaching portion 9. The member 8 also has an attaching portion 13 suitably secured to its section 5 of the frame of the conveyer and at each side of the attaching portion 13 integral side plates 14 are provided, the plates 14 having inwardly projecting apertured bosses or hinge ears 15 which are transversely aligned with the hinge ears 10. Beyond the hinge ears 15 the side plates 14 are apertured to provide lock lugs 16 cooperable with the lock lugs 11. A hinge pin 17 is extended through the aligned openings of the hinge ears 10 and 15 of each hinge and is suitably secured and held against displacement as by means of cotter pins, whereby members 7 and 8 of each hinge are pivotally connected. As will be understood, from Figures 2 and 4, the lock lugs 11 and 16 have a plurality of openings 18 and 19 therein, the openings being designed to be selectively registered. As these openings 18 and 19 are located at different distances from the axis of the hinges 35 and at different angular intervals about the hinge, the sections of the frame of the conveyer may be and are locked in the desired angular positions relative to each other by inserting a lock pin 20 through one or the other sets of aligned openings of the lock lugs of the hinges. Thus, as shown in Figure 4, the lock pin 20 is inserted through the openings 18 and holds the section 5 in one angular adjustment. By taking this lock pin 20 out of the openings 18, bringing the openings 19 into alignment or registration and inserting the lock pin 20 into the registering openings 19 these sections may be secured in a different angular adjustment. Thus, in the embodiment shown, the sections 5 of the frame may be locked in a straight position or at a practical working angle. The lock pin 20 is formed with an offset end portion 21 constituting a handle member and this handle member together with a cotter pin 22 serves to releasably secure the hinges 6 and sections 5 locked in the selected adjustment. One of the advantageous features of this construction resides in the fact that the lock pin 20 may be quickly and easily removed and reinserted, thereby making the conveyer adjustment convenient and expeditious.

As above stated, and as clearly shown in Figure 5, the frame of the conveyer is generally of inverted channel shape and has a body

portion 25, depending side flanges 26 and in-turned ribs 27 extending along the lower edges of the flanges 26. The body portion 25 and side flanges 26 are preferably integral and the ribs 27 may be integral with the side flanges 26 or may be separate pieces welded to the side flanges. These ribs 27 have the desirable and necessary extent along their flanges 26 but at intervals they may be cut away. A support is provided for the conveyer frame and consists of a pair of frame members 28 which are preferably angles and which are secured to the upper ends of standards or uprights 29, the lower ends of which uprights 29 are fastened to the frame members 30 of the trencher. Fixed supporting shafts 31 are carried by the frame members 28, the shafts 31 being located adjacent the ends of the frame members and extending transversely therebetween. On each shaft 31 a pair of supporting rollers 32 is rotatably mounted. Each roller 32 has a hub 33 and on these hubs the lower edges of the flanges 26 and the ribs 27 bear, whereby the frame of the conveyer is supported. Each roller 32 also has a peripheral flange 34 and the flanges 34 of the rollers bear against the outer face of the flanges 26 of the frame, whereby to prevent lateral displacement of the frame. The frame is held down on the hubs 33 of the rollers 32 by means of rollers 35 engaging the upper faces of the ribs 27 and mounted to rotate about an axis fixed with respect to the shafts 31. Preferably these rollers 35 are rotatably mounted on supports 36, clamped, as at 37, to the shafts 31. The rollers 32 are held against lateral displacement by means of sleeves 38 mounted on the shafts 31 and interposed between the rollers and the frame members 28. A sleeve 39 is mounted on each shaft 31 and interposed between the supports 36. In this way spaced points of support are provided for the conveyer and the conveyer is free to partake of proper shifting movement while being properly supported against upward or lateral as well as downward displacement.

At each end of the conveyer frame a reinforcing plate 40 is secured. Across each end of the frame 4 a transversely extending channel 41 is provided, each channel 41 being secured in position by a connecting angle 42, suitably secured to the plate 40, the frame 4 and the channel 41. Transversely extending angles 43 may also be provided to afford a means of attachment for a hoist line 90 and to stiffen and strengthen the conveyer frame.

On each channel 41, brackets 44 are provided and on these brackets 44 a shaft 45 is rotatably supported. Each shaft 45 has fixed thereto a conveyer mounting and driving drum 46. Around the drums 46 an endless conveyer member or belt 47 extends. To enhance the driving engagement of the drums 46 with the belt 47 they are of general convex

form in that they are largest at their centers and taper toward their ends. For the major portion of its extent, however, the upper run of the conveyer belt 47 is transversely dished to provide a trough like conveyer which minimizes spilling of the spoil. This trough-like form of the body of the upper run of the conveyer belt is obtained by providing belt supporting roller assemblies 48 at spaced intervals along the frame 4 of the conveyer. Each roller assembly 48 comprises a pair of supporting brackets 49 in which a center shaft 50 and lateral shafts 51 are fixed. The shaft 50 is horizontal but the shafts 51 incline upwardly and outwardly from the shaft 50. A central horizontal roller 52 is mounted for free rotation and on the shaft 51 end rollers 53 are mounted for free rotation on the shafts 51. The end rollers incline upwardly and outwardly from the horizontal center roller and thus dish or concave the upper run of the conveyer belt to provide a conveyer of trough like form.

The lower run of the conveyer belt passes below the guide rollers 54 and above guide rollers 54^a as shown in Figure 4.

Means is provided for driving the conveyer in any adjustment thereof and this means comprises an endless sprocket chain 55 trained over sprocket wheels 56 fixed to the shafts 45. The upper run of the sprocket chain 55 passes over a drive sprocket 57 and under guide pulleys 58 arranged on the opposite sides of the guide sprockets 59. The lower run of the sprocket chain 55 meshes with a lower sprocket 59 which serves to take up the slack in the lower run and prevent whipping thereof.

Means is provided for shifting the conveyer frame longitudinally irrespective of the angular adjustment of its sections. This means comprises a sprocket chain 60 having its ends yieldably connected as indicated generally at 61 to the ends of the conveyer frame 4 and having its intermediate portion running under guide pulleys 62 and over a drive sprocket 63. The guide pulleys 62 are rotatably mounted on fixed supporting shafts 64 carried by the frame members 28, sleeves 65 being loosely mounted on the shafts 64 and interposed between the pulleys 62 and the frame members 28 for preventing lateral displacement of the pulleys on their shafts. The drive sprocket 63 is fixed to a rotatable shaft 66 mounted on suitable bearings provided therefor in the frame members 28 and driven in either direction from the usual or a suitable source of power and by means of suitable gearing. Two of the gears employed to drive the shafts 66 are shown at 67.

Each yieldable connection 61 between the ends of the chain 60 and the ends of the conveyer frame comprises a pair of rollers 70 rotatably mounted on a pin 71 pivotally connected to the adjacent end link of the chain 60 and to the bifurcated and apertured head

of a sliding bolt 72. The roller 70 rides back and forth on tracks 73 provided by brackets fastened to the conveyer frame and shaped as shown in Figure 5. The shank of the sliding bolt 72 is slidably fitted in an opening provided therefor in a bracket 74 fixed to the conveyer frame just beyond the tracks 73. A coil spring 75 encircles the bolt 72 and has one end abutting the bracket 74 and its other end abutting a nut and washer 76 adjustably mounted on the bolt 72. Each spring 75 is tensioned to draw its bolt 72 outwardly through the guide 74 whereby to tension the chain 60 and yet this spring 75 may yield to some extent to absorb drive shocks and to compensate for the differential that exists when raising the conveyer, since the conveyer is hinged at a point not concentric with the hinge point of the chain. The rollers 70 and tracks 73 coact to retain a straight line motion.

While the trough-like character of the upper run of the belt minimizes the spilling of spoil, any spoil that is displaced over the sides of the upper run is thrown clear of the conveyer by means of deflectors 80 extending along the sides of the conveyer and supported on brackets 81 as shown in Figures 2 and 5.

With a spoil conveyer of this character the section of the conveyer frame may be locked to provide a substantially straight line conveyer or they may be locked in a position to provide a cradle type of conveyer and this conversion may be easily and quickly carried out. As shown in Figure 2, the hoist line 90 is connected as at 91 to apertured attaching lugs provided on the angle 43 adjacent the outer end of the conveyer frame. The hoist line is reeved in the usual manner over suitable guide pulleys and around a suitable winding drum. By locking the hinges to secure the sections 5 of the frame 4 in proper angular relation and disconnecting the hoist line 90, the conveyer is converted into a cradle type. By using the hoist line and leaving at least one end free the conveyer can be hoisted to a practical height for discharging the spoil or may be swung to an upright position for travel. All of these adjustments and operations can be carried out quickly and easily and without and dismantling or laborious and time consuming bolting and unbolting. When the conveyer is shifted in, it is entirely practical to load trucks or otherwise discharge the spoil at a comparatively high elevation and, as there are a number of hinge points, the conveyer frame can be raised quickly to clear obstructions even when shifted in. These advantages are had and yet the conveyer is supported at two spaced points of support.

Another important feature of the invention resides in the particular frame construction which is located centrally under the conveyer belt. This frame construction is adapted to

the use of the roller assembly which forms a trough-like upper run for the major portion of the extent of the upper run, thereby minimizing the spilling of the spoil. Moreover, 5 any spoil that is spilled is deflected clear of the machine. This is an important advantage when it is considered that serious trouble has been experienced by reason of dirt or spoil getting between the belt and the conveyer frame. When such dirt or spoil gets wet it 10 clings to the underside of the belt and acts as a lubricant diminishing the friction between the driving drums and the belt which results in the belt slipping upon the drums and which 15 impairs the capacity of the belt to convey away the spoil. The shifting means for the conveyer frame employing as it does a chain and yieldable connections between the chain and the conveyer frame makes it possible and 20 practical to support the frame in almost any convenient or proper way, support it at two points to obtain stability and rigidity, and to raise the conveyer to any angle or elevate it to an upright position, and withal maintain 25 the proper mesh of the shifting members.

The invention claimed is:

1. A spoil conveyer for trenching machines comprising a frame member made up of a plurality of sections, means for hingedly connecting the sections, readily releasable means adapted to lock any number of the sections in adjusted angular position relative to each other and also adapted to leave any number of the sections free, means for supporting the frame member for longitudinal shifting, means for shifting the frame, an endless conveyer member mounted on the frame, means for driving the endless conveyer member and a hoist line releasably connected with the outer end of the frame.

2. A spoil conveyer for trenching machines comprising a single frame member made up of a plurality of sections, means for hingedly connecting said sections, readily 45 releasable means for locking the sections in any angular adjustment, means for supporting the frame at spaced points and permitting movement of the frame back and forth, means for holding the frame against vertical displacement from its support, means for shifting the frame back and forth, an endless conveyer member, means on the frame for mounting the conveyer member thereon, and 50 means for driving the endless conveyer member.

3. A spoil conveyer for trenching machines comprising a single frame member made up of a plurality of sections, means for hingedly 60 connecting adjacent ends of sections together, readily releasable means for securing the adjacent ends of the sections in adjusted angular relation, means connected with the frame member for shifting the same longitudinally, an endless conveyer member

mounted on the frame, and means for driving the endless conveyer member in all positions of the spoil conveyer.

4. A spoil conveyer for trenching machines comprising a frame member made up of a plurality of sections, means for hingedly connecting the sections, readily releasable means adapted to lock any number of the sections in adjusted angular position relative to each other and also adapted to leave any number of the sections free for relative pivotal movement, means for supporting the frame member for longitudinal shifting, a flexible shifting element having yieldable connections with the frame member, a gear element for actuating the flexible shifting element, an endless conveyer member mounted on the frame, means for driving the endless conveyer member, and a hoist line releasably connected with the outer end of the frame member.

5. A spoil conveyer for trenching machines comprising a frame member made up of a plurality of sections, hinges connecting the adjacent ends of the sections, each hinge being made up of a pair of hinge members pivotally connected together, a removable lock pin co-operable with each pair of hinge members for locking the sections thereof in any one of a plurality of angular adjustments, each lock pin when removed leaving its hinge members free and the sections associated with such hinge members free to partake of relative pivotal movement, means for supporting the frame member for longitudinal shifting movement, a sprocket chain extending longitudinally of the frame, yieldable connections between the sprocket chain and the frame, a driving sprocket wheel meshed with the chain and mounted to rotate about an axis fixed with respect to the frame, an endless conveyer member mounting on the frame, means for driving the endless conveyer member, and a hoist line releasably connected with the frame.

6. A spoil conveyer for trenching machines comprising a frame member made up of a plurality of sections, hinges connecting the adjacent ends of the sections each hinge being made up of a pair of hinge members pivotally connected together, a removable lock pin co-operable with each pair of hinge members for locking the sections thereof in any one of a plurality of angular adjustments, each lock pin when removed, leaving its hinge members free and the sections associated with such hinge members free to partake of relative pivotal movement, means engaging the frame member at spaced points for supporting the frame member for longitudinal shifting movement, a sprocket chain extending longitudinally of the frame, yieldable connection between the sprocket chain and the frame, a driving sprocket wheel meshed with the chain and mounted to rotate about an axis fixed with respect to the frame, an endless conveyer member

member mounted on the frame, means for driving the endless conveyer member, and a hoist line releasably connected with the frame.

7. A spoil conveyer for trenching machines comprising an endless conveyer belt, a single frame member extending longitudinally and centrally of the conveyer belt and having means for supporting and driving the belt, the side edges of the frame being spaced inwardly from the side edges of the conveyer.

10 8. A spoil conveyer for trenching machines comprising an endless conveyer belt, a single frame member extending longitudinally and centrally of the conveyer belt and having means for supporting and driving the belt, the side edges of the frame being spaced inwardly from the side edges of the conveyer, and deflectors mounted on the conveyer frame but spaced outwardly therefrom and extending downwardly and outwardly adjacent the side edges of the belt.

15 9. A spoil conveyer for trenching machines comprising a conveyer belt, a single frame member extending longitudinally of the belt intermediate of the side edges thereof, means at the ends of the frame member for mounting and driving the belt, and roller assembly at spaced intervals along the frame and engaging the upper run of the belt, each roller assembly including a central roller and upwardly and outwardly extending lateral rollers, all mounted on the single frame member, whereby to give the upper run of the belt a trough-like form.

20 30 10. A spoil conveyer for trenching machines comprising a single frame member made up of a plurality of sections, means for hingedly connecting the sections, readily releasable means for locking the sections in angular adjustments, a support for the frame having means engaging the same at spaced points, and an endless conveyer member mounted on the frame, means for driving the endless conveyer member, and means for shifting the frame back and forth and including a chain with yieldable connections between the chain and frame, and a driving sprocket wheel meshed with the chain and rotatably mounted on the support of the conveyer.

25 40 45 50 11. A spoil conveyer for trenching machines having an endless belt, a shiftable frame member, a flexible shifting member located within the confines of and protected by the endless belt and connected with the frame member and power means coacting with the flexible shifting member for moving it to shift the frame member back and forth.

55 60 65 12. A spoil conveyer for trenching machines having a frame member made up of adjustable sections and releasable means for locking the section in various angular adjustments, a flexible shifting member having yieldable connections with the frame member, and means coacting with the flexible

shifting member for shifting the frame back and forth.

13. A spoil conveyer for trenching machines having a frame member, means engaging the frame member at spaced points to support the frame member for back and forth movement, a flexible shifting member having yieldable connections with the frame member, and means coacting with the flexible shifting member for shifting the frame back and forth.

75 14. A spoil conveyer for trenching machines having a frame member made up of adjustable sections and releasable means for locking the section in various angular adjustments, means engaging the frame member at spaced points to support the frame member for back and forth movement, a flexible shifting member having yieldable connections with the frame member, and means coacting with the flexible shifting member for shifting the frame member back and forth.

80 15. A spoil conveyer for trenching machines having a frame member and means for shifting the frame member back and forth and comprising a flexible shifting member, means for driving the same and yieldable connections between flexible shifting member and the conveyer frame.

85 90 16. A spoil conveyer for trenching machines comprising a frame and means for shifting the frame back and forth including a sprocket chain located intermediate the side edges of the frame, means for driving the sprocket chain including a sprocket wheel meshed therewith, and connections between the ends of the chain and the frame.

- having direct supporting engagement with the frame member proper to maintain it against downward displacement while permitting the same to move back and forth, means preventing lateral displacement of the frame member while permitting it to move back and forth, means preventing upward displacement of the frame member while permitting it to move back and forth and a conveyer belt mounted on said frame member and having its runs encompassing the several means.
20. A spoil conveyer for trenching machines comprising a frame member, rollers having direct supporting engagement with the frame member proper to maintain it against downward displacement and having peripheral flanges preventing lateral displacement of the same, and means preventing upward displacement of the frame member.
21. A spoil conveyer for trenching machines comprising a single frame member of channel shape, supporting shafts spaced from each other in the direction of the length of the frame member and extending transversely of the frame member below the same means on said shafts supporting the frame member against downward displacement while permitting the same to move back and forth, means on said shafts preventing lateral displacement of the conveyer while permitting it to move back and forth, means on said shafts to prevent upward displacement of the conveyer while permitting it to move back and forth, an endless conveyer belt, and means at the ends of the frame member for supporting and driving said belt, said belt having its lower run extending below said shafts.
22. A spoil conveyer for trenching machines comprising a single frame member of substantially inverted channel shape, said frame member having a body portion and depending side flanges provided with inturned ribs, a support for the frame member including rollers having hubs with which the lower edges of the flanges and the ribs engage, and also having peripheral flanges engageable with the flanges of the frame to prevent lateral displacement, means cooperable with the inturned ribs to hold the frame on its support.
23. A spoil conveyer for trenching machines comprising a frame member of substantially inverted channel shape in cross section, said frame member having a body portion and depending side flanges formed with inturned ribs, fixed supporting shafts spaced from each other in the direction of the length of the frame member, rollers on said shafts having hubs engaged with the underside of the ribs and the lower edges of the side flanges, said rollers having peripheral flanges engaged with the outer faces of the side flanges, supports fixed to the shafts, and rollers mounted on the supports and engaging the upper faces or the ribs.
24. A spoil conveyer for trenching machines comprising a frame member of substantially inverted channel shape in cross section, said frame member having a body portion and depending side flanges formed with inturned ribs, fixed supporting shafts spaced from each other in the direction of the length of the frame member, means on said shafts supporting the frame member against downward displacement while permitting the same to move back and forth, means on said shafts to prevent lateral displacement of the frame member while permitting the same to move back and forth, supports fixed to the shafts, and rollers mounted on the supports and engaging the upper faces of the ribs.
25. A spoil conveyer for trenching machines having a single frame member of channel shape and having a body portion and side flanges provided with ribs, and means coacting with the side flanges and ribs to constrain the frame member to back and forth movement.
26. A spoil conveyer for trenching machines comprising an endless conveyer belt, a single frame member of channel shape in cross section extending longitudinally and centrally of the conveyer belt and having a means at its ends for supporting and driving the conveyer belt, the sides of the frame being spaced inwardly from the side edges of the conveyer.
27. A spoil conveyer for trenching machines comprising an endless conveyer belt, a single frame member of channel shape in cross section extending longitudinally and centrally of the conveyer belt and having a means at its ends for supporting and driving the conveyer belt, the sides of the frame being spaced inwardly from the side edges of the conveyer, said frame being made up of a plurality of sections, hinges pivotally connecting the sections and readily releasable locking means cooperable with the hinges for securing different angular adjustments.
28. A spoil conveyer for trenching machines comprising an endless conveyer belt, a single frame member of channel shape in cross section extending longitudinally and centrally of the conveyer belt and having a means at its ends for supporting and driving the conveyer belt, the sides of the frame being spaced inwardly from the side edges of the conveyer, means coacting with the channel shaped frame to support it against upward or lateral as well as downward displacement, and means for shifting the frame on its support.
29. A spoil conveyer for trenching machines comprising a frame member made up of a plurality of sections connected to each other for relative angular adjustment, readily

releasable means adapted to lock any number of the sections in any one of a plurality of adjusted angular positions relative to each other, an endless conveyer mounted on the frame and operable thereabout with the frame sections in various adjustments, and means operable to drive the endless conveyer with the sections thereof in any selected adjustment.

30. A spoil conveyer for trenching machines comprising a frame member made up of a plurality of sections, hinges pivotally connecting the sections for relative angular adjustment, readily releasable locking means adapted to secure any number of the sections in adjusted angular position relative to each other, and an endless conveyer member mounted on the frame and operable thereabout with the sections of the frame member secured in various adjustments.

20 In witness whereof, I hereto affix my signature.

ROBERT L. BROWN.
